UNITED STATES PATENT OFFICE.

THOMAS E. MURRAY AND EDWIN B. RICKETTS, OF NEW YORK, N. Y.

METHOD OF AND APPARATUS FOR COKING CRUDE-OIL RESIDUUM.

1,293,866.

Specification of Letters Patent. Patented Feb. 11, 1919.

Application filed November 20, 1917. Serial No. 202,936.

To all whom it may concern:

Be it known that we, THOMAS E. MURRAY and EDWIN B. RICKETTS, citizens of the United States, residing at New York, in the county of New York and State of New York, have invented a certain new and useful Improvement in Methods of and Apparatus for Coking Crude-Oil Residuum, of which the following is a specification.

10 The invention is a method of coking crude oil residuum, and an apparatus for carrying said method into effect.

The residuum is caused to pass over the inner surface of a casing or shell in the form of a thin layer, and while so passing is subjected to a current of hot gas. Because of its enlarged evaporating surface, the volatile products in said layer are rapidly driven off, while the coke simultaneously is deposited upon the shell surface, from which it is removed from time to time. The apparatus herein disclosed embodies a vertical cylindrical shell, through which the current of hot gas is caused to pass upwardly, while the residuum projected upon the inner surface of said shell in the form of expanding jets from a plurality of delivery pipes flows down said surface and so surrounds the upwardly rising gas current.

In the accompanying drawings—

Figure 1 is a vertical section of our coking tower. Fig. 2 is a top view.

Similar letters of reference indicate like parts.

A is a cylindrical still shell, open below and supported in any suitable way preferably above a pit B which contains water, into which the lower end of said shell enters. On one side of the shell is a chamber C, into which enters a gas burner D, the heated gas current from which passes upwardly through the shell and escapes at the duct E, which here opens into shell A through the head F.

Above the shell is a ring duct G which by pipe H communicates with a source of supply of the crude oil residuum to be coked, any suitable means (not shown) being provided for forcing said residuum under pressure through said pipe H to ring G. Depending from ring G and passing through head F are a number of short delivery pipes I. The outlet ends of said pipes are flared, and said ends are turned horizontally, so that the escaping residuum is projected from

each of said pipes I against the inner surface of shell A, and then flows downwardly along said surface in a thin layer, sheet or plurality of streams. The thin layer of residuum is acted upon by the ascending current of hot gas from burner D, and because of its thin or film-like character, the volatile products—in the case of crude oil residuum, fuel oil and wax tailings—are rapidly evaporated, and pass off, as stated, by duct E. The coke is deposited upon the inner surface of the shell, and can be readily detached therefrom by percussion on the outside of said shell, so that it falls off and drops into the water in pit B, from which it is removed by any suitable implement through the portion of said pit, at J, which is uncovered by the shell.

The object of flaring the ends of delivery pipes I is to project the residuum as flaring or expanding jets, and in this way insure that the layer, sheet or streams which flow down the inner surface of the shell shall be thin, and so readily volatizable by the hot gas.

The pipe H is here shown surrounded by a jacket K, through which may be passed hot gas from any suitable source.

We claim:

1. The method of coking crude oil residuum, which consists in causing said residuum to flow in a thin layer over the inner surface of a chamber, and simultaneously causing a current of hot gas to pass over said thin layer; whereby the volatile products of said residuum are evaporated and the coke caused to deposit on said surface.

2. A coking tower, for crude oil residuum, comprising a vertical tubular shell open at its lower end and having a head at its upper end, an escape duct for volatile products communicating with the top of said tower, means for delivering the residuum to be coked in a plurality of jets against the inner surface of said shell near the top thereof, and means for delivering a current of hot gas into said shell near the bottom thereof; whereby said residuum is caused to descend said inner shell surface in a thin layer surrounding the rising column of hot gas in said shell.

3. A coking tower for crude oil residuum, comprising a vertical tubular shell open at its lower end, and having a head at its upper end, an escape duct for volatile products communicating with the top of said shell,

- means for establishing a current of hot gas upwardly through said shell to said escape duct, a plurality of ducts entering said tower through said head and having their 5 lower ends outwardly turned and disposed respectively in proximity to the inner surface of said shell to deliver jets of said residuum against said shell, and means for delivering said residuum to said ducts; whereby 10 said residuum is caused to descend said inner shell surface in a thin layer surrounding the rising column of hot gas in said shell.
4. A coking tower as claimed in claim 3, including a ring duct supported above said 15 tower, to which duct the inlet pipe for residuum and the delivery ducts entering said tower are connected.
5. A coking tower for crude oil residuum, comprising a vertical tubular shell, a plurality of delivery ducts for said residuum 20

disposed within said shell and having their ends flared and turned to project said residuum in expanding jets against the inner surface of said shell, means for conveying said residuum to said ducts, and means for 25 causing a current of hot gas to pass over the layer of residuum projected against said shell surface.

6. A coking tower as claimed in claim 5, including means for causing said current of 30 hot gas to pass over said layer of residuum in a direction opposite to that of the flow of said layer over said surface.

In testimony whereof we have affixed our signatures in presence of two witnesses.

THOMAS E. MURRAY.
EDWIN B. RICKETTS.
